Primary Examiner—Martie Thompson*Attorney, Agent, or Firm*—Leydig, Voit & Mayer, Ltd.[57] **CLAIM**

The ornamental design for a writing instrument container for display stand, as shown and described.

DESCRIPTION

FIG. 1 is a top perspective view of the writing instrument container for display stand showing our new design;

FIG. 2 is a front elevational view thereof;

FIG. 3 is a top plan view thereof;

FIG. 4 is a left side elevational view thereof, the right side being a mirror image thereof;

FIG. 5 is a rear elevational view thereof;

FIG. 6 is a bottom plan view thereof; and,

FIG. 7 is a top perspective view thereof, the display stand and writing instruments depicted by means of broken lines being for illustrative purposes only and forming no part of the claimed design.

*Fig. 1**Fig. 2**Fig. 6**Fig. 3**Fig. 5**Fig. 4**Fig. 7*UNITED STATES PATENT AND TRADEMARK OFFICE
CERTIFICATE OF CORRECTION

PATENT NO. : **Des. 353,840**

DATED : **December 27, 1994**

INVENTOR(S) : **Charles W. Dietterich, et al**

It is certified that error appears in the above-identified patent and that said Letters Patent is hereby corrected as shown below:

On the Title Page, Item [73], "Binney & Smith, Inc." should be —Binney & Smith Inc.—.

In the claim, second line, "stand, as" should be —stand as—.

In the description, line 9, ";" and," should be —; and—.

Signed and Sealed this

Fourteenth Day of March, 1995
